(57) **CLAIM**

The ornamental design for a beverage container, as shown and described.

DESCRIPTION

FIG. 1 is a perspective view of a beverage container showing our new design;

FIG. 2 is a rear lower perspective view of the beverage container;

FIG. 3 is a front view of the beverage container;

FIG. 4 is a rear view of the beverage container;

FIG. 5 is a left side view of the beverage container;

FIG. 6 is a right side view of the beverage container;

FIG. 7 is an enlarged top view of the beverage container; and

FIG. 8 is an enlarged bottom view of the beverage container. The broken lines showing in the figures are included for the purpose of illustrating portions of the beverage container that form no part of the claimed design.

1 Claim, 7 Drawing Sheets
